UNITED STATES PATENT OFFICE.

JESSE L. CABRAL, OF BROCKTON, MASSACHUSETTS.

SCREEN-FRAME.

1,285,613.

Specification of Letters Patent. Patented Nov. 26, 1918.

Application filed June 24, 1918. Serial No. 241,463.

To all whom it may concern:

Be it known that I, JESSE L. CABRAL, a citizen of the United States, and resident of Brockton, in the county of Plymouth and

5 State of Massachusetts, have invented certain new and useful Improvements in Screen-Frames, of which the following is a specification.

This invention relates to screen frames, 10 and has for its object to provide such a frame that is made up of a plurality of sections whereby the frame may be shipped in a knock-down condition, said frame sections being also adjustable with respect to each 15 other, so that the frame may be extended to fit openings of different sizes.

A further object of the invention is to provide frame runs formed of a plurality of sections, which sections are also endwise 20 adjustable with respect to each other, for the purpose of accommodating the screen frames as adjusted to fit openings of different sizes.

With these and other objects in view, the 25 invention consists of certain novel features of construction, as will be more fully described, and particularly pointed out in the appended claims.

In the accompanying drawings:

30 Figure 1— is a front view showing my improved adjustable screen frame mounted to slide in extendible screen runs or guides, the latter being partially in section.

Fig. 2— shows one of the frame sections 35 as it appears when blanked out of sheet stock.

Fig. 3— shows the strip as folded upon itself and the doubled edge portion bent up at substantially a right angle to the remaining portion.

Fig. 4— shows the doubled edge of the frame section in the act of being bent at the 40 cut in the lips to form a right angle corner, the metal over the corner being continuous.

Fig. 5— is a perspective view showing a portion of two of the corner section members, the end of one being large enough to receive 45 that of the other within its fold.

Fig. 6— is a face view showing one of the 50 corner members and a portion of an adjacent section as fitted into the doubled frame portion.

Fig. 7— is a section on line 7—7 of Fig. 6, showing the end portion of one frame as 55 fitting inside of that of the other frame and

showing a portion of the screen fabric as retained between the lips of these portions by rivets.

Fig. 8— is a perspective view illustrating the two sections of the extendible run, the 60 smaller end of one fitting the larger end of the other.

Referring to the drawings, 10 designates the strip of metal from which the frame sections are made as blanked out of sheet stock, 65 the same being provided with a plurality of rivet holes 11 along its opposite edges, these edges being slit inwardly from the opposite margins as at 12 for the reason presently described.

After this block has been so formed it is folded longitudinally through its middle, forming two spaced-apart lips 13 and 14, the under lip 14 extending beyond the opposite lip to facilitate positioning the screen cloth 75 therebetween. The doubled edge 15 of this folded strip is now bent up at substantially a right angle to these lips 13 and 14, to stiffen the frame and form a broad sliding edge, the fold of this metal is so formed as 80 to leave an opening in the fold a little larger at one end of the strip than at the other so that the smaller end 22 of one section may fit into the larger end 23 of the next section, see Figs. 5 and 6, upon connecting the sections together.

In order to form the corner in the sections, I bend this strip at the cut 12, as shown in Fig. 4, so that the lips of one portion will 85 fit over those of the other portion and when the portions are brought to a right angle, the edge 16 at the cut of one portion will abut against the angled wall of the doubled edge portion of the other, thereby forming a stop to determine the extent of the bend 90 and limit it to 90°. It is now only necessary to pass the rivet 17 through these four overlapping, interlocking lip portions and the corner member is completed.

To form the frames four of these corner 100 members are made in this manner and the end of each corner section is arranged to fit and slide into the folded portion of the next adjacent corner member. It will be seen by such adjustability the frame may be 105 made the size to fit any desired opening within the limit of its height. If it should be desired to provide a frame larger than the greatest length of the corner members then intermediate members of the same cross 110

section and of any desired length may be inserted into the ends of these angled sections to provide a frame of any desired size.

After the size of the frame has been determined and the parts riveted together it is now only necessary to bend up the lips 13 and 14 and extend the edge of the wire screen 24 between them, then pass rivets 18 through the holes in the lips and through the meshes of the screen cloth thereby binding the whole firmly together.

It is found in practice to be of advantage in many cases to employ split rivets so that when desired the screen may be readily taken apart and the size changed to fit other openings, in which case it is only necessary to refit the screen cloth in the frame and the new sized frame is again complete.

Another feature of this invention is the provision of trough-shaped edge runs 19 and 20 which are made in sections, each section being tapered in the direction of its length whereby any two may be made to fit one within the other and which sections are adapted to be relatively adjustable so as to accommodate adjustable screen frames of different heights. These trough-shaped runs are provided with screw holes 21 at their ends whereby they are fastened to the casing of the opening.

One of the features of this invention is that the parts of the frame and the run may be all made and sold in a knockdown condition to facilitate shipping and handling. Then again by forming these parts so that any two sections will fit together, the purchaser of a set of parts will have no difficulty in assembling them as one frame section will fit nicely and slide within the other thus being able to readily adjust the frame to the desired size, which feature is true of the trough-shaped run strips which are in a tapering form so that the small end of one will fit into the large end of any of the others and be longitudinally extendible with respect to each other to accommodate frames of different sizes.

By my improved construction this screen frame may be completely assembled and applied to a window, door or other opening without the expense of any mechanical skill.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. A screen frame made of a strip of sheet metal folded lengthwise upon itself providing a frame having two oppositely-disposed spaced-apart walls, the edges of said walls providing a slightly separated pair of lip portions between which the screen cloth is held, the folded edge portion of the strip being bent up at substantially a right angle to said double lip portion, both of said lip portions being cut transversely and said folded edge portion bent at these cuts to form a right angle corner with the metal continuous thereover, the cut portions of said lips over-lapping each other at the corner forming four ply of metal there, and means for securing said over-lapping corner lips together.

2. A screen frame made of a plurality of telescoping sections, each section being formed of a strip of sheet metal folded lengthwise upon itself forming a frame having a pair of oppositely disposed spaced apart walls, the edges of said walls providing a slightly separated pair of lip portions between which the screen cloth is held, the folded edge portion of the strip being bent up at substantially a right angle to said lip portions, said lips being cut transversely and said folded edge bent at the cut to form a right angle corner with the metal continuous thereover, said lip portions over-lapping each other at the corner forming four thicknesses of metal there, and means for securing said over-lapping lip portions together, one end of each of said telescoping sections being adapted to fit and slide into the corresponding end of the next hollow section whereby the size of said frame may be varied.

In testimony whereof I affix my signature

JESSE L. CABRAL.
